(57) **CLAIM**

I claim the ornamental design for a bottle, as shown and described.

DESCRIPTION

FIG. 1 is a rear perspective view of a bottle design in accordance with the invention;

FIG. 2 is a front elevational view of the bottle design of FIG. 1;

FIG. 3 is a rear elevational view of the bottle design of FIG. 1;

FIG. 4 is a right side elevational view of the bottle design of FIG. 1;

FIG. 5 is a left side elevational view of the bottle design of FIG. 1;

FIG. 6 is a top view of the bottle design of FIG. 1; and, FIG. 7 is a bottom view of the bottle design of FIG. 1. The broken lines in the drawings including the repeating circular details on the bottle handle and around the base of the bottle illustrate the portions of the bottle that form no part of the claimed design.
